GARMENT HANGER

Albert J. Bellg, Toledo, Ohio

Application August 26, 1958, Serial No. 52,379

Term of patent 14 years

(Cl. D80—8)

Fig. 2

Fig. 3

The characteristic features of my design for a garment hanger as disclosed reside in the end shoulder portions having the configuration shown.

I claim:

The ornamental design for a garment hanger, as shown and described.
